[57] CLAIM

The ornamental design for an egg cup with spoon, as shown and described.

DESCRIPTION

FIG. 1 is an oblique perspective view of the egg cup with spoon;

FIG. 2 is a right side view of the egg cup with spoon, as shown in FIG. 1;

FIG. 3 is a left side view of the egg cup with spoon;

FIG. 4 is a front elevational view of the egg cup with spoon;

FIG. 5 is a rear elevational view of the egg cup with spoon;

FIG. 6 is a top view of the egg cup with spoon;

FIG. 7 is a bottom view of the egg cup with spoon;

FIG. 8 is a perspective view of the egg cup with spoon showing the spoon portion only, the cup portion removed for ease of illustration;

FIG. 9 is a right side view thereof;

FIG. 10 is a left side view thereof;

FIG. 11 is a front elevational view thereof;

FIG. 12 is a rear elevational view thereof;

FIG. 13 is a top plan view thereof; and,

FIG. 14 is a bottom plan view thereof.
